RUMBLE SEAT DISAPPEARING TOP

George Alexandre Eno, Lowell, Mass.

Application December 13, 1934, Serial No. 757,364

1 Claim. (Cl. 296—98)

The invention relates to improvements in a rumble seat disappearing top in which said top and its individual parts are joined together in a way such that when not in use, will allow said top and its individual parts when in their proper position, and held in said position by means of snaps and swivel buttons, to be rolled in or out of the storing case at will by semi-automatic means; and the objects of the improvements are, first, to allow said top and its component parts when in an inoperative position to be stored in as small a case as possible in a position favorable to both the action of said top when in and not in use, and to the occupants of the rumble seat; second, to afford facilities for the proper adjustment of said top from its inoperative position in the storing case to its operative position on the rumble seat, and vice versa; third, to minimize the working time of setting said top in a working position on the rumble seat from its inoperative position in the case and vice versa.

One form of the invention is illustrated in the accompanying drawings in which Figure 1 is a rear right hand side elevation of the rumble seat disappearing top in position to cover the entire rumble seat; Figure 2 is a right hand elevation of the storing case for the rumble seat top in two of its working positions; Figure 3, an enlarged right hand rear elevation of a supporting brace socket in a working position; Figure 4, an enlarged frontal elevation of the socket for the brace in a working position; Figure 5, a partial plan of the rumble seat disappearing top with its horizontal bar top supports and its braces laid out horizontally, the left side curtain being equal in size and shape to the right side; Figure 6 being a horizontally sectional view of the fabric and material used in constructing the rumble seat disappearing top; Figure 7, a side elevation showing one of the braces with a snap post, said snap post to allow the snap on the side curtains to be put in; Figure 8 is a rear end elevation of the bare frame with its side braces, both said braces being in an operative and inoperative position, said frame used as a rear support of the rumble seat disappearing top; Figure 9 being an enlarged rear end elevation of the storing case; Figure 10 is a left end elevation of an enlarged central portion of the left side, said centrally located portion supporting the swivel bearing arm, showing the flattened end of the winding drum; Figure 11 is a right end elevation of an enlarged

central portion of the right side, said centrally located portion supporting the swivel bearing arm, with the ordinary round bearing, working in conjunction with the left end bearing, both being integral parts of the main drum; Figure 5 12 is an enlarged right hand elevation of the storing case shown partly in section showing the manner in which the rumble seat disappearing top is rolled in.

The rear half of an automobile body having 10 a rumble seat compartment 1, its support beams 7, running parallel underneath the metal covering of said rumble seat body, and the back rest 6, of said rumble seat in an open position, constitute the frame work of the machine as 15 shown in Figure 1.

The rumble seat disappearing top 2, after being unwound from its roll 28, (see Figure 12) out of its storing case 10, is shown in an operative position in Figure 1, said rumble seat disappearing 20 top being composed of its top two sides and a rear and front curtains joined to the top 2, all with flexible windows 5, (Figure 5) a front horizontal bar top support 3¹, and rear horizontal bar 25 top support 4¹, said front and rear horizontal bar top supports being joined to the lower side of the top 2 by means of an innermost layer of felt 11, 11 being glued to the top part of the horizontal bar top supports, and an inner layer of fabric 12, 30 lying between 11, and the bottom part of top 2, 35 being sewed thereon, said horizontal top supports being covered by a bottom layer of fabric 13, 13 being sewed on each side of said horizontal bar top supports to the bottom part of fabric 12 and top 2, 3¹, and 4¹ being hinged at 15, (see 40 Figure 8) to braces 3 and 4, said braces having a snap post 17, (Figure 7) 17 being used to hold the snap covers 17¹ in place, (see Figure 5) 17¹ being on the two side and rear curtains; the front and 45 rear horizontal bar top supports are identical in all respects to each other except for the stop motion pin 40, (as shown in Figure 8) 40 being at each end of the horizontal bar top support 4¹; on the lower side, in the center of the afore- 45 mentioned horizontal bar top supports 3¹ and 4¹, a swivel and hand operated button 14, is riveted on said bars in a way such as to allow said swivel and hand operated button to turn around its axis so that the braces 3 and 4 can be held in an in- 50 operative position (as shown on the left hand side of Figure 8) so as to allow the front and rear horizontal top supports with their braces to be rolled in or out of storing case 10; the right hand part of Figure 8, shows braces 4 in an operative 55

position, and the dotted lines being the aforementioned brace in an inoperative position.

The socket 16, (see Figures 3 and 4) there being one for each brace, is a rectangular box with inside dimensions slightly larger than the dimensions of the aforementioned brace, socket 16 providing a resting place for the brace 16, having an integral ear 36, on the top part of said socket, and another integral ear 36, on the lower part 10 of 16. A thumb screw 18 being joined to a swivel washer 41, (as shown in Figure 3) to allow a greater area of contact and pressure between 41 and the braces 3 and 4.

The storing case 10 previously referred to, and 15 shown in a right hand side elevation in Figure 2, also shown in another right hand side elevation with part of the inside of said storing case shown in Figure 12, said storing case also shown in a front elevation in Figure 9, can be moved around 20 its axis and held in any angular position desired by a series of radial screw holes 31, 31 being held in contact with a screw pin 22, held in the lower part of arm 9, the dotted position showing the most desired position; storing case 10, is composed 25 of a top half of a case 25, a bottom half of a case 26, similar in size and shape to 25, 25, and 26 being hinged at 27, said storing case being shown in Figures 9 and 12 partly in section showing its spring 33, held in its roll 28, by a pin 44, 30 said roll showing the two extreme horizontal supports 29 and 30, hinged in their bearings 43 and 42, 42 held by means of a flattened side 35,

said arms 9 being held in place to beams 7, by a means of screws 23 and nuts 34.

The features of the invention are perfectly carried out in the manner shown in Figure 12, where it will be seen that the top 2, with its side and rear curtains in an inoperative position, and its front top support 31, is rolled in on its roll 28, by means of a spring 33, said roll and spring being the ordinary kind of window curtain roll, said top 2, extending from its roll 28, in an inoperative position to its rear top support 41, and top support 41 having an extended pin 40 at each end, acting as a stop motion for the top 2, said pin resting in the groove 19.

I claim:

The combination, in a rumble seat disappearing top, of a flexible top with its sides and rear curtains, having front and rear rectangular top supports with braces, the width of said top, joined in a stationary position to the lower part of the 20 aforementioned top, said top and top supports with their braces being capable of being rolled in or out of a storing case, preferably octagonal in shape, having a wedge in an inclined plane located in the lower front part of the aforementioned 25 storing case, also having an extended outer opening, rectangular in shape, the width and depth of the front opening of said storing case, facilitating the in or out movements of the aforementioned top and its component parts.

GEORGE ALEXANDRE ENO.
